UNITED STATES PATENT OFFICE.

PAUL WILLIAM SCHURE, OF NEWHAVEN, MISSOURI.

HAME-TUG ATTACHMENT.

SPECIFICATION forming part of Letters Patent No. 760,650, dated May 24, 1904.

Application filed April 30, 1903. Serial No. 155,055. (No model.)

To all whom it may concern:

Be it known that I, PAUL WILLIAM SCHURE, a citizen of the United States, residing at Newhaven, in the county of Franklin and State of Missouri, have invented certain new and useful Improvements in Hame-Tug Attachments; and I do hereby declare the following to be a full, clear, and exact description of the invention, such as will enable others skilled in the art to which it appertains to make and use the same.

My invention has relation to harness, and more particularly to an attachment for hames whereby a perfect coöperating union between the tug and the hame is attained, with a desired degree of flexibility or yielding conformation of said parts; and my invention consists of certain novel features of combination and construction of coöperating elements, as will be hereinafter clearly set forth, and pointed out in the claim.

The prime object of my invention is to provide suitable means for connecting the tug with the hame which will permit of a maximum degree of flexibility and at the same time enable the tug and hame to be very quickly connected and disconnected, as desired.

Other objects and advantages will be hereinafter made clearly apparent, reference being had to the accompanying drawings, which are made a part of this application, and in which—

Figure 1 shows a perspective view of my invention complete. Fig. 2 is a longitudinal central section of the tug and a contiguous part of the hame. Figs. 3 and 4 show coöperating parts separated from each other. Fig. 5 shows a perspective view of the preferred means employed for connecting the tug member with the hame-staple. Fig. 6 is a transverse section of the hame-staple, showing a reduced portion thereof ready to coöperate with the member carried by the tug.

In order to conveniently refer to the various details of my invention and coöperating accessories, numerals will be employed, the same numeral applying to a similar part throughout the several views.

Referring to the numerals on the drawings, 1 indicates a section of the hame of the usual or any preferred construction, also provided

with the hame-staple 2, having upon its upper side the recessed portion 3 of sufficient width to pass freely through the slotted opening 4 formed in the forward end of the member 5, it being understood that said slotted opening 4 preferably opens to the rear and terminates forwardly in a vertically-disposed, preferably cylindrical, opening 6, extending transversely entirely through the member 5, said opening 6 being designed to afford a seat for the member 7 of the staple 2, said member 7 being round in cross-section. It is therefore obvious that by properly entering the recessed portion 3 in the slotted opening 4, which may be done by swinging the rear or slotted end of the member 5 forwardly, the opening 6 may be placed in position to receive the member 7. After the member 7 is entirely seated in the opening 6 and the staple 2 has been swung to the rear so that it and member 5 are disposed so as to occupy substantially the same plane said parts will be held against all possibility of separation until the member 5 is brought around at an angle to the staple-section which will permit the recessed portion 3 to enter the slotted opening 4, as will be obvious.

The member 5 is adapted to be pivotally connected to the tug-terminal 8, which latter usually consists of a suitable piece of iron properly shaped to be received by the end of the tug, to which it is permanently attached in any preferred way, as by riveting or the like.

The forward end of the anchoring shank or member 8 is shaped to fit between the bifurcated end 9 of the member 5, where it is pivotally secured to move in the planes of the member 5 and staple 2, as by passing a rivet 10 through suitable registering apertures provided in the members 5 and 8, as will be obvious.

In order to permit a free pivotal union between the members 5 and 8 and at the same time prevent undue movement of said parts, I prefer in some instances to provide the extension 11 upon the end of the member 8, said extension being loosely received by the recess 12 in the bottom of the bifurcation of the member 5, there being sufficient play between the extension 11 and the recess 12 as to provide the requisite degree of flexibility or relative

movement of said parts. By forming the parts in this manner the lug or extension and the recess can each be formed by casting at the same time that member 5 and shank 8 are formed, and they are so located as to be concealed, thereby permitting of a neater and cheaper construction than where exposed lugs or extra pins are used, and the recess is shielded from the entrance of dirt or foreign substances 5
10 which would prevent the free operation of the pivoted connection, and by forming a close fit between the forward end of the shank 8 and the walls of the bifurcated end 9 and making the pivot-holes and pivot 10 at right angles to the axis of the opening 6 the pivoted motion is limited to the plane of the shank and the tug and all lateral movement between the shank and member is prevented. The lug 11 and recess 12, however, may in some 15
20 instances be wholly omitted, if desired, my purpose being to provide a cheap form of construction which will at the same time prove reliably efficient in all requirements placed upon such a union of parts.
25 It will thus be seen that the parts of my improved tug and hame attachment may be very cheaply and expeditiously manufactured and readily assembled each in its operative position, and while I have described the preferred combination and construction of parts 30 deemed necessary in carrying out my invention I wish to comprehend all substantial equivalents and substitutes that may be con-

sidered as falling fairly within the scope and purview of my invention.

Believing that the advantages and manner of using my improved tug and hame attachment have thus been made clearly apparent further description is deemed unnecessary.

What I claim as new, and desire to secure 40 by Letters Patent, is—

In a hame-tug attachment, a member, the rear end of which is bifurcated and the forward end is provided with a transversely-located lateral opening, said opening terminating forwardly in a circular opening, the axis of which circular opening is in the same plane with said bifurcation, and the walls of the bifurcated portion are perforated transversely and the bottom is provided with a recess, a 45 perforated shank between said walls, the forward end of which is provided with an extension to fit in said recess, a pin through said perforations, and a staple for securing the member to the hame, one arm of said staple 50 being recessed to pass through the lateral opening in said member, and the central part being round to fit in the circular opening, substantially as specified.

In testimony whereof I affix my signature in 60 presence of two witnesses.

PAUL WILLIAM SCHURE.
